CIGARETTE LIGHTER

Emile Alexis Jeremie Romain, Damprichard (Doubs), France, assignor to Anciens Etablissements Myon & Cie, Damprichard (Doubs), France, a limited-liability company of France

Filed Nov. 17, 1961, Ser. No. 67,565

Claims priority, application France May 20, 1961

Term of patent 7 years

(Cl. D48—27)

FIG. 1 is a side elevational view of a cigarette lighter showing my new design;

FIG. 2 is an end view thereof looking from the right of FIG. 1;

FIG. 3 is a top plan view thereof;

FIG. 4 is a bottom plan view thereof;

FIG. 5 is an end view thereof looking from the left of FIG. 1, and

FIG. 6 is an enlarged fragmentary cross-sectional view taken along section line 6—6 in FIG. 1.

The side of the lighter not shown is substantially the same in appearance as the side shown.

I claim:

The ornamental design for a cigarette lighter, as shown and described.
